UNITED STATES PATENT OFFICE.

WILLIAM M. HOFFMAN, OF BUFFALO, NEW YORK, ASSIGNOR TO GENERAL FUEL APPARATUS CORPORATION, OF BUFFALO, NEW YORK, A CORPORATION OF DELAWARE

HYDROCARBON-BURNER.

1,401,403.

Specification of Letters Patent. Patented Dec. 27, 1921.

Application filed June 7, 1920. Serial No. 387,002.

To all whom it may concern:

Be it known that I, WILLIAM M. HOFFMAN, citizen of the United States, residing at Buffalo, county of Erie, State of New York, 5 have invented a certain new and useful Improvement in Hydrocarbon-Burners, and declare the following to be a full, clear, and exact description of the same, such as will enable others skilled in the art to which it 10 pertains to make and use the same, reference being had to the accompanying drawings, which form a part of this specification.

My invention relates to an improved oil burner, particularly to that type of burner 15 adapted to utilize the cheaper, heavier grades of fuel oil and the object is to secure the maximum efficiency from a given supply of fuel by the use of my improved burner herein-after described and claimed.

20 In the drawings,—

Figure 1 is a plan view of my burner.

Fig. 2 is a section taken on the line 2—2 of Fig. 1.

25 Fig. 3 is a section taken on the line 3—3, of Fig. 1.

Fig. 4 is a section partly in elevation taken on the line 4—4 of Fig. 1.

Fig. 5 is an elevation of the rear end.

My improved burner comprises upper and 30 lower burner plates in the form of hollow casings indicated as *a* and *b* respectively. The lower plate carries upwardly projecting end flanges *b*¹, *b*² partially closing the opening at the ends. The interior of these casings is filled with a refractory, porous substance such as asbestos, indicated as *c*, which is supplied with fuel oil through conduit *d* leading from a suitable source of fuel supply and discharging into an oil passageway *d*², 35 which passageway extends the entire length of each casing and connects them together so as to form an oil circuit extending through each casing supplied from the conduit *d*. The interior of this oil passageway is loosely 40 filled with a refractory, or porous substance, 45 not shown in the drawing, in order that the views may appear more clearly.

The wall of the passageway *d*² where such passageway extends through the casing is 50 perforated as at *e* to permit the fuel oil flowing therethrough to enter the casing proper through the perforations. The action of the refractory porous filler will be of course in each instance to delay the movement of 55 the fuel oil in order that the temperature

thereof may be raised even to the point of volatilization before it passes out through the perforated face of the burner plates.

These burner plates are positioned one above the other, their opposed faces being 60 perforated as at *f* to permit the passage of oil therethrough. These plates are spaced from each other so as to form a combustion chamber therebetween, such chamber being closed at the front and rear except as hereinafter indicated, but open at the ends to 65 permit of an air draft to be drawn therethrough. Each plate or casing is shaped so as to flare outwardly at the center so as to form an enlarged central portion in such 70 combustion chamber. This enlarged central portion forms the combustion chamber proper and opening axially therein from the rear is conduit *h* provided with nozzle *h*² adapted to project a jet of steam or air into 75 the interior thereof, along the face of the burner plates. This vapor jet will create a forced draft through the central portion of the combustion chamber which will also produce side drafts through the open ends of the 80 burner along the face of the burner plates drawing the burning products of combustion and air into the central portion of the combustion chamber along the face of the burner plates causing a thorough mixing of the 85 burning hydrocarbon particles and air and drawing the same into the enlarged central portion where the entire burning mass will be forced along the face of the burner plates thoroughly mixing the steam or air from the 90 nozzle with the burning gaseous products and completing the combustion.

The conduit *h* is shown with the pipes *j* and *i* provided with control valve *j*² and *i*² respectively, which pipes lead to supply 95 reservoirs not indicated, one being the conduit for the passage of steam and the other a conduit for the passage of air under pressure.

A disk regulator valve of known design, 100 indicated as *k*, provided with apertures *k*² adapted to register with apertures through the rear wall of the casing is provided as shown to regulate admission of air from the rear around the conduit *h*.

At the mouth of the enlarged portion of the combustion chamber is a funnel-shaped projector *g* adapted to project the flame forward for utilization in connection with such apparatus as may be desired.

In the operation of this device, the forced draft created through the central portion of the burner by the steam or air jet will cause an air draft along the face of the perforated 5 burner plates. Air drawn along these perforated faces will mix with the burning particles of hydrocarbon and the entire burning mass will be carried to the enlarged central portion of the combustion chamber where- 10 upon, being further mixed with the steam or air under pressure from the nozzle h^2 , combustion will be completed. The restricted area of the combustion chamber at the sides into which a limited amount of air will be 15 admitted, will tend to mix this air with the burning particles of hydrocarbon before combustion has been completed and the entire burning mass will be drawn toward the central enlarged portion of the burner for 20 completion of combustion on the completion of the mixing of the several products.

What I claim is:

1. In a hydrocarbon burner, an upper and lower plate, such plates spaced from each 25 other and so formed as to provide a combustion chamber therebetween of enlarged extent intermediate its ends, said burner plates formed of a refractory porous material through which fuel oil is adapted to 30 percolate to the interior of the burner.

2. In a hydrocarbon burner, a pair of opposed burner plates comprising hollow casings filled with a refractory porous sub- 35 stance, the interior face of said plates being perforated to permit the passage of fuel therethrough, means for supplying liquid fuel to the interior of said hollow casings so that it may percolate through the porous refractory filler to the interior of the burner.

40 3. In a hydrocarbon burner, an upper and lower perforated burner plate spaced from each other so as to provide a combustion chamber therebetween open at its ends to provide an air passageway, said plates so formed that the combustion chamber will be 45 of enlarged extent intermediate its ends, each of said plates provided with an exterior adjacent wall of refractory porous material, means for supplying fuel oil to the 50 outer surface of said wall.

4. In a hydrocarbon burner, an upper and lower burner plate spaced from each other so as to provide a combustion chamber therebetween open at the ends to provide an air 55 inlet, means for forcing a vapor jet through such combustion chamber at an angle to the air draft through the open ends.

5. In a hydrocarbon burner, a pair of horizontal burner plates spaced from each 60 other so as to provide a combustion chamber therebetween open at opposite ends to provide an air inlet but enlarged near the center, means for forcing a steam or air jet through such enlarged portion of the combustion chamber, in such a manner as to

draw the products of combustion along the face of the burner plates into the enlarged central portion of the chamber and force the same through such enlarged central portion along the face thereof.

6. In a hydrocarbon burner, an upper and lower burner plate, opposed faces of which are perforated to permit the passage of oil therethrough, means for supplying oil thereto, such plates spaced from each other to provide a combustion chamber therebetween open at the end to provide an air draft passageway, such plates so formed that said combustion chamber is narrowed as it approaches the air inlet openings.

7. In a hydrocarbon burner, a pair of opposed burner plates comprising hollow casings, the opposed faces of which are perforated to permit the passage of oil therethrough, the interior of such casings being filled with a refractory porous material, means for supplying oil thereto, said plates spaced from each other to provide a combustion chamber therebetween with an enlarged central portion and narrowed end portions, such end portions open to the atmosphere, means for forcing a vapor draft through such central portion in such a manner as to draw the burning particles of hydrocarbon and air along the face of the burner plates into the enlarged central portion and force the same through said enlarged portion of the burner along the face thereof.

8. In a hydrocarbon burner, an upper and lower burner plate comprising hollow casings filled with a porous refractory material, opposed faces of which casings are perforated to permit the passage of fuel therethrough, means for supplying fuel to the interior of such casings, said plates spaced from each other so as to provide a combustion chamber therebetween with an enlarged central portion and narrowed end portions, such combustion chamber open at the ends to provide an air inlet, means for forcing a vapor jet axially through such enlarged central portion, means for regulating the admission of air through an auxiliary air inlet to such enlarged portion of the combustion chamber.

9. In a fuel oil burner, a combustion chamber comprising opposed porous refractory burner plates spaced from each other, means for supplying fuel oil to the outer surface of said plates, said combustion chamber formed with an enlarged central portion and narrowed end portions open to the atmosphere.

10. In a fuel oil burner, a combustion chamber comprising a pair of opposed spaced-apart burner plates formed of porous refractory material so constructed that fuel oil may be supplied to the outer surface thereof, said plates so formed and relatively

- arranged that the central portion thereof is of enlarged extent narrowed as it approaches opposite ends and open at said ends to provide an atmospheric inlet, means for projecting a vapor jet through the enlarged central portion of said combustion chamber in such a manner as to create a forced draft through the narrowed end portions of the chamber.
- 10 11. In a fuel oil burner, a hollow combustion chamber comprising two opposed spaced-apart walls formed of porous refrac-
- tory material so positioned as to provide atmosphere inlet openings, means for supplying fuel oil to the outer surface of said porous 15 refractory chamber walls, said chamber so formed that air will be drawn through the inlet openings and through a confined portion of relatively small diameter to a central portion of substantially enlarged diameter.
- 10 11. In a fuel oil burner, a hollow combustion chamber comprising two opposed spaced-apart walls formed of porous refrac-

In testimony whereof, I sign this specification.

WILLIAM M. HOFFMAN.
